WELL EQUIPMENT

John S. Page, Long Beach, Calif., assignor to Page
Oil Tools Inc., Long Beach, Calif., a corporation
of California

Application April 19, 1946, Serial No. 663,560.

19 Claims. (Cl. 166—12)

1

This invention has to do with well equipment and is more specifically concerned with a device for use in an oil well to facilitate the operation or production of the well after it has been drilled, and it is a general object of the invention to provide a device or unit of apparatus that is effective to anchor and pack off a string of tubing or the like employed to conduct fluid out of a well.

It is a general object of my present invention to provide a device of the general character above referred to that can be used either in a flowing well or a well being pumped, to anchor and support a flow string or tubing in the well. When the device that I have provided is set in operating position a part of the load of the tubing may be imposed upon it while part of the load of the tubing can be carried in tension from the top of the well.

A further object of my present invention is to provide a structure of the general character referred to that can be run into a well which is full of fluid, whereupon the device can be tripped so well fluid enters the tubing to develop a head or pressure that actuates packing means enabling gripping means or slips to be set.

It is a further object of my invention to provide a structure of the general character referred to which includes a drain passage or by-pass by which a head of fluid that might otherwise develop above the device between the tubing and casing is relieved or drained into the casing below the device.

Another object of my present invention is to provide a structure of the general type referred to involving means whereby fluid can be released from the tubing above the packing means to relieve pressure so that the structure can be released.

It is a further object of my invention to provide a device of the type referred to including a safety means that can be ruptured or actuated if necessary to relieve pressure from the packing structure to release it so that the equipment is released for withdrawal from the well.

The various objects and features of my invention will be fully understood from the following detailed description of a typical preferred form and application of the invention, throughout which description reference is made to the accompanying drawings, in which:

Fig. 1 is a longitudinal detailed sectional view of the lower portion or half of the structure that I have provided showing it within a casing and carrying a length of tubing that extends down-

wardly from it to a suitable point in the well or in the casing. Fig. 2 is a view similar to Fig. 1 of the upper portion or upper half of the tool, Fig. 1 showing the parts in set or operating position and Fig. 2 showing the parts in a position to be run into the well. Fig. 3 is an enlarged detailed sectional view showing the fluid passage that conducts fluid from the tubing to the chamber between the packers. Fig. 4 is an enlarged

10 view similar to Fig. 3 showing the safety means provided for releasing pressure from between the packers, when necessary. Fig. 5 is an enlarged detailed sectional view of a part of the construction shown at the lower portion of Fig. 1, it being 15 a part of the by-pass means included in the structure. Fig. 6 is an enlarged detailed transverse sectional view taken as indicated by line 6—6 on Fig. 1. Fig. 7 is a side elevation of the seat part shown in Fig. 5 with a part broken

20 away to appear in section. Fig. 8 is an enlarged detailed view illustrating the bayonet slot construction employed in the master control means. Fig. 9 is an enlarged detailed transverse sectional view taken as indicated by line 9—9 on Fig. 1. Fig. 10 is a perspective view of the lower end 25 portion of a go-devil that may be employed to release or actuate the bleeding means incorporated in the construction. Fig. 11 is an enlarged detailed sectional view taken as indicated by line 11—11 on Fig. 1, and Fig. 12 is a view similar to Fig. 2 showing the upper portion actuated so as to release the tool for removal from the well.

The device that I have provided is useful generally where it is desired to pack off and anchor the lower end portion of a string of tubing or the like, and in most cases the device is most useful when connected in a string of tubing or on the lower end thereof, and is operated in a typical well casing, and therefore I will in the following description make reference to such a situation or application of the invention.

In the drawings the well casing is designated A and the tubing extending above the apparatus, 45 which I will refer to as upper section, is designated B, while the tubing or like element extending below the apparatus, which I will term the lower tubing section, is designated C. The casing A may be considered a usual well casing fixed in a well bore and the upper tubing section B may be a usual or ordinary string of tubing extending to the top of the well where it may be suitably supported in any usual manner. The lower tubing section C may extend a suitable 50 distance below the apparatus and if the well is

to be pumped it may be equipped to carry a pump, whereas if the well is flowing under head it may be equipped to meet such condition.

The apparatus that I have provided involves, generally, a main section which I will term a main body D, anchor means E carried by the body to grip the well casing A, and packing means F carried by the body preferably below the anchor means E and constructed to be actuated by fluid pressure. The apparatus further includes what may be termed a hydraulic control system which involves, generally, a main or master control means G, bleeder means H, by-pass means J and a safety pressure releasing means K.

The main body D of the apparatus is an elongate tubular part or structure which, in effect, forms the frame or body to which the other parts or elements are related. In the preferred form of the invention the tubular body is a straight or plain tubular structure which, in effect, forms a continuation of the tubing sections and acts to conduct fluid through the apparatus.

The anchor means E that I have provided is carried by the body D preferably at or around the upper end portion thereof, and it involves, generally, slips 10, a support 11 for the slips 10, a control ring 12, links 13 coupling the slips to the control ring, and a release spring 13a.

The support 11 is shown surrounding the upper end portion of the body D and is carried by a coupling member 14 that screw threads to the upper end of the body D and serves as a means of connecting the means G with the upper end portion of the body. The slip support is in the nature of an enlargement and has tapered faces or guideways 15 that slidably support the slips 10. The faces extend upwardly and outwardly as shown in Fig. 1, and the guideways and slips may have cooperating dove-tailed parts, as shown in Fig. 6, so that the slips are effectively coupled to the support.

The slips which are spaced circumferentially around the support 11 are shiftable longitudinally of the apparatus between a down position where their outer faces 16 are clear of the inner wall of casing A and an up position where their outer faces are in gripping engagement with the casing A, as shown in Figs. 1 and 6. In practice the outer faces 16 of the slips may be formed with teeth or wickers in the manner common to devices of this type.

The control ring 12 is slidably supported on the body D below the slips 10 and their support 11 and the links 13 have their lower ends connected to the ring by pivotal connections 17 and have their upper ends connected to the lower ends of the slips 10 by pivotal connections 18. Through this construction as the ring 12 is moved or reciprocated vertically on the body D the slips 10 are moved up and down relative to the support 11. The spring 13a surrounds the body D and acts under compression between the lower end of the support 11 and the ring 12 to normally yieldingly urge the ring 12 downward on the body so that the slips are normally held in a down or retracted position. In practice the ring is recessed at 19 to receive the lower end portion of the spring 13a so that the spring can be made of substantial length.

The packing means F that I have provided is carried by the body D and is preferably located immediately below the means E. The packing means preferably includes a pair of spaced opposed packers 20 which face inwardly or toward

each other so that pressure applied between them acts to expand them outwardly into pressure engagement with the inner wall of the casing A.

The upper packer 20 is preferably in the form of a downwardly and outwardly flared ring or sleeve of rubber or the like carried by a sleeve 21 slidably supported on the body D. The sleeve 21 may be an extension or continuation of the ring 12 so that the upper packer moves in unison with the ring. The packer 20 is proportioned so that its small or upper end fits tight around the sleeve 21 and it is confined between a stop ring 22 and a retainer 23 held by a nut 24. The stop ring 22 bears against the lower end of the ring 12 while the retainer 23 slidably fits over the lower end portion of the sleeve 21 and is held up by the nut 24 threaded on the lower end portion of the extension 21.

The lower packer is located on the body D at a point spaced somewhat below the upper packer and it includes an upwardly and outwardly flaring sleeve or collar of rubber or the like carried on a sleeve 21a between a stop ring 22a and a retainer 23a which is held by a nut 24a. The sleeve 21a is similar to the sleeve 21 in that it is slidable on the body D. In the case illustrated the sleeve 21a is shown as an upward extension of a part of the means J to be hereinafter described. The stop ring 22a seats against the said part of means J while the retainer 23a is held in place by the nut 24a threaded on the upper end portion of the sleeve 21a.

A port 25 is provided through the wall of body D between the packers just described so that the chamber 26 around the body between the packers is in free communication with the interior of or longitudinal passage through the body D.

The main or master control means G controls communication between the space X between the casing and tubing above the packing means F and the interior of the apparatus. In the preferred arrangement the means G is located immediately above the means E above described and it is a compact unit or construction confined to a position immediately above the means E. Further, it is preferred that the means G serve as a fluid coupling or fluid connection between the upper end of the body D and the lower end of tubing section B, or such part as may be interposed between the lower end of tubing section B and the means G.

The means G in the form illustrated in the drawings, is, generally, a valve means and it includes what I will term a tubular valve body 27, the lower end of which is threaded or otherwise suitably coupled to the coupler 14 that carries the support 11 of means E. A valve sleeve 28 surrounds and is movable longitudinally of the body 27. One or more ports 29 are provided in the valve body 27 intermediate its ends and one or more ports 30 are provided in the valve sleeve 28. The valve sleeve may be related to the body so that the ports 29 and 30 are out of register as shown in Fig. 12 or they may be positioned or related so that the ports 29 and 30 are in register, as shown in Fig. 2. Sealing means preferably in the form of spaced sealing rings 31 act between the valve body and valve sleeve to prevent leakage lengthwise between these parts in the region of the ports just described. In the particular case illustrated the sealing rings 31 are carried by the valve body above and below the ports 29 and they cooperate with the inner wall or bore 32 of the valve sleeve, as clearly shown in Figs. 2 and 12 of the drawings.

The means G includes, in addition to the valve parts above described, friction means or friction members 33 coupled to the valve sleeve and frictionally engaging the inner wall of casing A; and a releasable connection is provided between the valve body and the valve sleeve to hold the valve sleeve down when the ports 29 and 30 are in register. The spring members 33 which may be in the nature of leaf springs, are shown having their lower end portions secured to the lower end portion of the valve sleeve 28 by fastening means 34 while the upper end portions extend under a protective lip 35 on a cap 36 applied to the upper end of the valve sleeve. The middle or central portions of the springs 33 are bowed outwardly so that they slide or frictionally bear on the inner wall of the casing A to resist rotative or lengthwise movement in the casing.

The control for the structure just described preferably includes a bayonet type control means and as shown in the drawings it may include a pin 37 projecting from a part fixed relative to the valve body as for instance from the coupler 14, and an L-shaped or bayonet type slot 38 provided in the lower end portion of the valve sleeve 28. In the preferred form of my invention I form the bayonet slot so that it includes a longitudinal slot portion a, a lateral slot portion b, and a recess c at the inner end of the lateral portion b as shown in Fig. 8 of the drawings. The bayonet type control is such that when the pin 37 is in the inner or lateral portion b of the slot 38 the apparatus can be moved freely up or down in the casing A without effecting movement of the valve sleeve 28 relative to the valve body 27. When the movement of the apparatus is down relative to the casing A, or during the operation where the apparatus is being run into the well, the spring members 33 frictionally engage the inner wall of the casing A to hold the pin 37 down, or in engagement with the recess c in the lateral portion b of the slot 38. Thus the recess c prevents the pin 37 from being displaced or otherwise moved from the lateral portion b of the slot 38. To close the valve of the means G the apparatus is raised in the well, as by raising of the upper tubing section B. This relative movement removes the pin 37 from the recess c and when the valve body 27 is rotated the pin 37 is moved out of the portion b and into the longitudinal portion a of the slot 38. If the valve body 27 is then moved down, as by lowering of the upper tubing section B the pin 37 will move down through the slot portion a and a relative positioning of parts such as is shown in Fig. 12 may result, causing communication to be cut off between ports 29 and 30.

The bleeder means H that I have provided is preferably located immediately above the means G and may serve to couple the means G with the upper section B of tubing. The bleeder means H may, so far as the broader principles of my invention are concerned, be any suitable form or type of construction that can be operated to establish a bleeder opening or connection between the interior of the tubing and the space X between the tubing and casing. The bleeder means H that I have elected to illustrate involves a simple tubular body section 40 having ports 41 and an internal bore 42 carrying a control sleeve 43. The control sleeve carries packing rings 44 which are spaced apart vertically and when the control sleeve is in its normal position the packing rings 44 are above and below the ports 41 so the sleeve 43 serves as an effective closure preventing leakage either into or out of the tubing through the

ports 41. In the case illustrated a suitable coupler 45 is provided connecting the lower end of the body 40 of means H with the upper end of the valve body 27 of means G.

The sleeve 43 of the means H may be shifted or moved longitudinally in the bore 42 to uncover or open the ports 41 by any suitable means or device lowered through the tubing to engage or grapple the sleeve. As an example of a means 10 that may be used, a go-devil may be dropped through the tubing to strike and move the sleeve 43. In the drawings I have shown a go-devil with a head 46 with spaced ribs 47 to guide it in the tubing and to engage the upper end of the 15 sleeve 43 for moving or driving the sleeve down from the position shown in Fig. 2 to that shown in Figs. 12 of the drawings. A suitable weight or sinker can be applied to the head 46, for instance, as shown, a length of sucker rod 48 may be attached to the head 46, so that it descends through the tubing in the desired manner.

The by-pass means J that I have provided serves to allow fluid that may leak into or accumulate in the space X between the tubing and casing and above the packing means F to escape past the packing means and into the casing A below the packing means. In the preferred form of construction the means J includes, generally, an elongate liner 50 extending substantially the 25 entire length of the body D and spaced within the body so that there is an annular drainage channel 51 established between the liner 50 and the body. An inlet port 52 is provided in the body D above the packing means F, say for instance where the spring 13 is located as shown in Fig. 1, so that fluid accumulating in the space X is free to enter the annular space 51 between the liner and body. At the lower end portion of the apparatus the means J includes a valve 30 structure that controls the passage or flow of fluid so that fluid can only flow down through the space 51. The particular construction illustrated includes a tubular center part 60 attached to the lower end of the body D by a coupling 61 and coupled to the upper end of tubing section C by a coupling 62. A jacket or case 64 surrounds the tubular center part 60 and the sleeve or extension 21 a above described is attached to the upper end of case 64. The lower end of case 64 is provided with a removable seat ring 65 and a valve 66 is slidably carried on the part 60 below the seat 65 and is normally yieldingly urged up by a spring 67 so that entrance into the case 64 is normally closed or sealed off. The valve 66 is an annular or sleeve-like member slidably carried on the part 60 and a sealing ring 68 is provided to maintain a fluid tight connection between these parts. Further, in practice a sealing ring 69 is preferably provided between the valve 66 and seat 65 to maintain a tight connection at this point. The upper end portion of the case 64 extends somewhat above the coupling 61 that joins the lower end of the body D to the part 60 so that there is an annular chamber formed at 45 70. Ports 71 in the lower end portion of the body D connect the annular space 51 with the chamber 70 and longitudinal channels 72 are provided in the exterior of the coupler 61 so that there is free passage of fluid down from the chamber 70 between the coupler 61 and case 64 to the interior of the valve seat 65. The upper end of the valve seat 65 is recessed or notched at 75 so that the parts cannot become engaged in a manner to seal off free communication between the passages 75 72 and the interior of the seat ring 65.

Since the body D is equipped with the liner 50 that is spaced within it I may establish the port 25 above described by providing a body of welding material at 80 to form a bridge between the body D and liner 50 through which bridge the port 25 is formed.

Through the construction that I have above described it will, under normal conditions, be possible to disengage the apparatus so that it can be removed from the casing at will. However, to provide communication from the chamber 26 between the packers 20 and the space X between the tubing and casing above the packing means F I provide the safety means K. The safety means K in its preferred form involves a plug 90 carried in an opening provided in the wall of the body D in the vicinity of the port 25. The plug 90 has a passageway 91 through it which passageway is normally closed by a break-disc 92 made tight by a sealing cup 93. Under normal conditions pressure in the chamber 26 will exceed that in the space X between the tubing and casing above the packing means F. Should it be desired to relieve the pressure from the chamber 26 a pressure can be established in the chamber 26 sufficient to exceed that in the space X and enough greater so that the break disc 92 fails. When the pressure in chamber 26 is relieved there will be an equal or corresponding pressure in both the chamber 26 and the space X allowing the packers 20 to be released from the casing.

In practice the apparatus that I have provided may be handled in various ways. For example, it may be lowered into a well or into the casing A on the lower end or in a string of tubing in much the same manner that an anchor or packer is lowered into a well. Under normal conditions as the apparatus is lowered into the well the slips 10 are down or retracted and the packers 20 will merely slide along on the inside of the casing A. Ordinarily it will be preferred that the means G be positioned so that the ports 29 and 30 are in communication so that pressures equalize around the various parts of the apparatus and do not in any way interfere with its free movement to the desired point in the casing A. It is to be understood, of course, that the means H is run into the well, set as shown in Fig. 2, so that the sleeve 43 closes the ports 41.

With the apparatus located at the desired point in the well the operator may manipulate the means G to close passage therethrough and to do this he raises the tubing slightly, then rotates the tubing enough to disengage the bayonet slot connection above described and then lowers the tubing slightly, enough so that the valve sleeve 28 is moved relative to the valve body 27 so the parts are positioned as shown in Fig. 12 where the ports 29 and 30 are cut off or out of communication. Fluid from the well or from the lower tubing section C will then flow up through the apparatus and into the upper tubing section B either by reason of the formation pressure or because of swabbing or the action of a pump, with the result that a head of pressure is established in the body D of the apparatus, which pressure is communicated through the port 25 into chamber 26. This pressure expands the packers 20 so that they become firmly set in sealing and gripping engagement with the casing A, and thus establish a point of resistance so that the tubing can then be lowered causing the support 11 of the means E to wedge the slips 10 outwardly, with the result that the downward pressure or at least a substantial amount of down-

ward pressure, is taken by the slip construction or the means E.

As the apparatus operates flow will occur up through the body D and out through the upper tubing section B. Should there be a leakage of fluid into the space X when the head or pressure of such accumulation becomes sufficient the valve 66 will be opened allowing such accumulated fluid to by-pass or drain so that it enters the casing A below the packing means F. It is to be observed however, that the valve 66 cooperates with the seat 65 to check any upward flow or escape of pressure with the result that pressure may accumulate in the casing below the packing means F and thus be utilized to force fluid up through the tubing.

When it is desired to remove the apparatus pressure conditions may be such that it is merely necessary to lift the tubing section B which causes the support 11 to lift out of or up relative to the slips 10 allowing the slips to release the casing, whereupon the packers will slide up through the casing. Should it be necessary to relieve the head of pressure acting on the packers in chamber 26 the means H may be opened or operated as by causing the sleeve 43 to be shifted to a position where the ports 41 are uncovered. Opening of the ports 41 will allow fluid in the tubing section B to drain into the space X between the tubing and the casing thus equalizing the pressure in chamber 26 and the space X, and thus relieving the pressure on the packers 20 so they can be moved in the casing. Another manner in which pressure can be relieved from the packers is by applying upward movement to the string of tubing so that the lower packer 20 is moved up applying pressure to the fluid in chamber 26 so that the break disc 92 is ruptured, allowing fluid in chamber 26 to escape into the by-pass. This latter operation can be used to advantage when the tubing is sanded up preventing escape of pressure out through the port 25.

As a more specific example of the use of my apparatus if it is to be used in a completed well it is lowered into the well on a string of tubing with the ports 29 and 30 in register, and when at the desired point in the well oil may be pumped down through the tubing to displace mud from the tubing and also from between the tubing and the casing. When this operation has been completed the means G can be operated as above described to close or cut off communication between ports 29 and 30 whereupon a swab may be run into the tubing and operated to move a fluid column up in the tubing. This swabbing operation will cause oil on the outside of the tubing to recede and liquid may be emptied from the casing above the tool. Thereafter the valve means J will close preventing any upward flow of fluid through the by-pass means.

Should the well prove to be wet or should it be desired to kill it for any other reason prior to removing the tubing, mud can be pumped down through the casing around the outside of the upper tubing section B to pass through the by-pass means J until mud enters and fills the space between the casing A and the lower tubing section C. When such handling of mud has been complete the tool will be free for removal as the fluid pressures will be equalized and the spring 13 will act to retract the slips so that as soon as the tubing section B is moved or picked up the means G operates, causing the ports 29 and 30 to register so mud can drain out of the tubing

through these ports as the tubing is pulled or withdrawn from the well.

Where the apparatus is used in a pumping well release of the tool may be effected without pumping mud into the well, for instance, the means H may be operated as by a go-devil or other suitable means to allow fluid to drain from the tubing. In a case where the tubing has become sanded up the operator may pick the tubing up or move it up to cause the lower packer 20 to move up and thus exert pressure in the chamber 26 to burst the breakable disc 92 which relieves pressure from the chamber 26 into the by-pass and thus allows the packer means to release and be freely movable in the casing A. As the apparatus is pulled from the well fluid on the outside of the tubing section B is free to drain through the by-pass means J.

Among the outstanding features of the apparatus that I have provided is that it is operable as above described to kill a well, for instance, a high pressure gas well, prior to any effort being made to release the packer or hoist the tubing from the well. Further, it is significant to note that with my apparatus I am able to hold the upper portion of tubing section B in tension while the tubing is packed off. It is further to be noted that I have provided a construction wherein the packers are of such design and relationship that they have limited contact with the wall of the casing and thus minimize the danger of the packers sticking to the casing. With my construction the fluid pressure behind the packers is the principal force effecting the seal, and when this pressure is relieved the packers are released and free to move. This feature of my construction is to be contrasted with the usual packer which presents a long surface in engagement with the casing and the weight of tubing is utilized as the means for effecting the pressure on the packer to cause sealing engagement with the casing. It is well known, of course, that a packer of rubber or the like, standing in pressure engagement with a casing over a long period of time and at the temperature prevailing in a well, tend to cause bonding of the packers with the casing and, consequently, when I provide packers having limited contact with the casing I minimize the danger of this vulcanizing or sticking action. Furthermore, by my construction I avoid or eliminate the usual column of mud that stands above the usual packer, making it difficult to remove.

Having described only a typical preferred form and application of my invention, I do not wish to be limited or restricted to the specific details herein set forth, but wish to reserve to myself any variations or modifications that may appear to those skilled in the art and fall within the scope of the following claims:

Having described my invention, I claim:

1. Apparatus for setting tubing in a casing including, a tubular body carried by and having communication with the tubing and having a lateral passage, packing means carried by the body below said passage and including spaced elements set in the casing by pressure from within the body, grip means carried by the body and engageable with the casing and including a casing engaging element held by the packing means and an element cooperating with the casing engaging element and shiftable with the body, and a flow control for the lateral passage including a valve member carried by the body and shiftable relative thereto into and out of position where it closes the passage.

2. Apparatus for setting tubing in a casing including, a tubular body carried by and having communication with the tubing, packer means carried by the body and engageable with the casing, means controlling communication between the tubing and casing above the packer means, a by-pass means around the packer means connecting the casing above the packer means with the casing below the packer means, and bleeder means releasable to drain fluid from the tubing into the casing above the packer means.

3. Apparatus for setting tubing in a casing including, a tubular body carried by and having communication with the tubing, packing means carried by the body and engageable with the casing and including two relatively movable packers, bypass means in the body extending past the packing means and connecting the interior of the casing above the packing means with the interior of the casing below the packing means, the body having an opening admitting fluid to the packing means between the packers, and a member carried by the body operable to release pressure from between the packers and to the bypass means upon the packers being forced one toward the other.

4. Apparatus for setting tubing in a casing including, a tubular body carried by and having communication with the tubing, packing means carried by the body and engageable with the casing and including two relatively movable packers, the body having an opening admitting fluid from the body to the packing means between the packers, casing gripping means carried by the body and engageable with the casing, means operably connecting the gripping means with the packing means, and a member connecting the gripping means and engaged with the casing and operable relative to the body to release pressure from between the packers upon the packers being forced one toward the other.

5. Apparatus for setting tubing in a casing including, a tubular body carried by and having communication with the tubing, packing means carried by the body and engageable with the casing and including two relatively movable packers, the body having an opening admitting fluid from the body to the packing means between the packers, casing gripping means carried by the body and engageable with the casing, means operably connecting the gripping means with the packing means, means carried by the body above the packing means controlling communication between the tubing and casing above the packing means, and a member carried by the body operable to release pressure from between the packers upon the packers being forced one toward the other.

6. Apparatus for setting tubing in a casing including, a tubular body carried by and having communication with the tubing, packing means carried by the body and engageable with the casing and including two relatively movable packers, the body having an opening admitting fluid from the body to the packing means between the packers, means carried by the body above the packing means controlling communication between the tubing and casing above the packing means, and a member carried by the body operable to release pressure from between the packers upon the packers being forced one toward the other.

7. Apparatus for setting tubing in a casing including, a tubular body carried by and having communication with the tubing, packing means

11

carried by the body and engageable with the casing and including two relatively movable packers, the body having an opening admitting fluid from the body to the packing means between the packers, bleeder means carried by the body releasable to drain fluid from the tubing above the packing means into the casing above the packing means, and a member carried by the body operable to release pressure from between the packers upon the packers being forced one toward the other.

8. Apparatus for setting tubing in a casing including, a tubular body carried by and having communication with the tubing, packing means carried by the body and engageable with the casing and including two relatively movable packers, the body having an opening admitting fluid from the body to the packing means between the packers, casing gripping means carried by the body and engageable with the casing and operably connected with the packing means, means carried by the body above the packing means controlling communication between the tubing and casing above the packing means, bleeder means carried by the body releasable to drain fluid from the tubing above the packing means into the casing above the packing means, and a member carried by the body operable to release pressure from between the packers upon the packers being forced one toward the other.

9. Apparatus for setting a tubing in a casing including a tubular body carried by and having communication with the tubing, spaced packers on the body engageable with the casing, the uppermost packer being shiftable longitudinally of the body, the body having an opening admitting fluid from the body between the packers to operate them, a wedge member on the body, slips operated by said member into engagement with the casing, means operatively connecting the slips with the shiftable packer, a lateral flow passage through the body above the packers from the inside of the body to the outside thereof, a sleeve on the body controlling said passage and having frictional engagement with the casing, and bypass means in the body extending past the packers and establishing communication between the interior of the casing above the packers and the interior of the casing below the packers.

10. Apparatus for setting a tubing in a casing including, a tubular body carried by and having communication with the tubing, spaced packers on the body engageable with the casing, the uppermost packer being shiftable longitudinally of the body, the body having an opening admitting fluid from the body between the packers to operate them, a wedge member on the body, slips operated by said member into engagement with the casing, means operatively connecting the slips with the shiftable packer, a lateral flow passage through the body above the packers from the inside of the body to the outside thereof, a sleeve on the body controlling said passage and having frictional engagement with the casing, bleeder means carried by the body above the packers releasable to drain fluid from the tubing into the casing above the packers, bypass means carried by the body extending past the packers and establishing communication between the interior of the casing above the packers and the interior of the casing below the packers, and a check valve carried by the body checking the flow upwardly in the bypass means.

11. Apparatus for use in connection with a casing and a tubing within the casing including, a central tubular body carried by the tubing and in communication therewith, a fluid pressure actuated packer means carried by the body to engage in the casing and including spaced opposed packers, grip means carried by the body to engage the casing, one of the packers being shiftable on the body, means operatively connecting the grip means and the shiftable packer, and a flow control carried by the body including an opening in the body connecting the tubing and casing above the packer means and a valve member controlling the opening and a friction member on the valve and engaging the casing whereby the valve is operated by manipulation of the tubing relative to the casing.

12. Apparatus for use in connection with a casing and a tubing within the casing including, a central rigid continuous tubular body connected to the tubing and having communication therewith, a fluid pressure actuated packer means on the body to engage in the casing, slip means carried on the body above the packer means to engage the casing and operated by the packer means, and a control for a lateral flow passage in the body including a valve member slidable on the exterior of the body above the packer means and controlling the passage and operated by manipulation of the tubing relative to the casing, the slip means including a support fixed on the body with upwardly and outwardly inclined faces and slips operable on said faces and coupled to the packer means.

13. Apparatus for use in connection with a casing and a tubing within the casing including, a central rigid continuous tubular body connected to the tubing and having communication therewith, a fluid pressure actuated packer means on the body to engage in the casing, grip means on the body above the packer means to engage the casing and operated by the packer means, and a control for a lateral flow passage in the body above the packer means including, a valve member on the body controlling the passage, friction members connected with the valve member to engage the interior of the casing, and a bayonet type control connection between the valve member and body.

14. Apparatus for use in connection with a casing and a tubing within the casing including, an elongate tubular main body, packer means carried by the body to engage the casing and including a packer shiftable along the body, slip means carried by the body and engageable with the casing and operatively connected with said packer, and means controlling communication between the tubing and casing above the packer means including a rigid tubular valve body connected with the upper end of said main body and projecting upward therefrom for connection with the tubing, the valve body having a lateral flow passage therethrough, a valve member controlling the passage and shiftable relative to said valve body, friction means on the valve member and engaging the casing, and a releaseable connection between the valve body and valve member.

15. Apparatus for use in connection with a casing and a tubing within the casing including, an elongate tubular body, packer means carried by the body to engage the casing and including longitudinally spaced packers one of which is shiftable along the body, slip means carried by the body to engage the casing and operatively

13

connected with said packer, and means controlling communication between the tubing and casing above the packer means, the body having a by-pass opening connecting the interior of the casing above the packer means with the interior of the casing below the packer means and extending through the packer means.

16. Apparatus for use in connection with a casing and a tubing within the casing including, an elongate tubular body, packer means carried by the body and engageable with the casing and including a packer shiftable along the body, slip means carried by the body and engageable with the casing and operatively connected with said packer, means controlling communication between the tubing and casing above the packer means, a by-pass extending through the packer means and connecting the casing above the packer means with the casing below the packer means, and a valve checking upward flow through the by-pass.

17. Apparatus for use in connection with a casing and a tubing within the casing including, an elongate tubular body, packer means carried by the body and engageable with the casing and including a packer shiftable along the body, slip means carried by the body and operatively connected with said packer, means controlling communication between the tubing and casing above the packer means and operated by manipulation of the tubing relative to the casing, and bleeder means releasable to drain fluid from the tubing into the casing above the packer means.

18. Apparatus for use in connection with a casing and a tubing within the casing including, an elongate tubular body, packer means carried by the body and engageable with the casing and including a packer shiftable along the body, slip means carried by the body and operatively connected with said packer, means controlling communication between the tubing and casing above

14

the packer means, a by-pass means around the packer means connecting the casing above the packer means with the casing below the packer means, and bleeder means releasable to drain fluid from the tubing into the casing above the packer means.

19. Apparatus for use in connection with a casing and a tubing within the casing including, an elongate tubular body, a fluid pressure actuated packer means carried by the body and engageable with the casing and including a packer shiftable along the body, slip means carried by the body and engageable with the casing and operatively connected with said packer, means controlling communication between the tubing and casing above the packer means, by-pass means around the packer means connecting the casing above the packer means with the casing below the packer means, and a normally closed fluid connection between the by-pass and packer means closed by a member subject to failure when pressure in the packer means exceeds that in the casing above the packer means.
